UNITED STATES PATENT OFFICE.

RICHARD S. TAYLOR, OF BUFFALO, NEW YORK.

DESIGN FOR A PEN-WIPER.

SPECIFICATION forming part of Design No. 30,557, dated April 18, 1899.

Application filed March 20, 1899. Serial No. 709,854. Term of patent 7 years.

To all whom it may concern:

Be it known that I, RICHARD S. TAYLOR, of Buffalo, in the county of Erie and State of New York, have originated and invented a new and useful Design for Pen-Wipers; and I do hereby declare that the following is a full, clear, and exact description thereof, reference being had to the accompanying drawings, forming a part of this specification.

10 My invention consists of a design for a pen-wiper, which will be fully hereinafter described and claimed.

15 In the drawings, Figure 1 is a front elevation of my design, and Fig. 2 is a side elevation of the same.

Referring to the drawings, it will be seen that the frame which supports the pen-wiper consists of the two legs 1 and 2, forming an arch. Each leg has a broadened base 3. Above 20 the junction of the two legs forming the arch

is the head portion 4, so shaped as to represent a fowl's head with eyes and the protruding beak 5 in front and the rear flat extension 6. The head is mounted or covered by the pointed cap 7, and over the arch formed by the two 25 legs 1 and 2 is the pen-wiper 8, forming a cape, above which is the bow 9. Across the front of the cape is the rectangular space for the reception of a suitable inscription.

I claim—

30 The design for a pen-wiper substantially as shown and described.

In testimony that I claim the foregoing as my own I affix my signature in presence of two witnesses.

RICHARD S. TAYLOR.
